BY J. R. GERMWAEG. TR.

UNITED STATES PATENT OFFICE.

JOHN K. BRODERICK, OF ST. LOUIS, MISSOURI.

DESIGN FOR A CIGAR OR SIMILAR ARTICLE.

42,414.

Specification for Design.

Patented Apr. 23, 1912.

Application filed April 7, 1911. Serial No. 619,630. Term of patent 14 years.

To all whom it may concern:

Be it known that I, JOHN K. BRODERICK, a citizen of the United States, residing at St. Louis, State of Missouri, have invented a new, original, and ornamental Design for Cigars or Similar Articles, of which the following is a specification, reference being had to the accompanying drawing, forming part thereof.

Figure 1 is an elevation of a cigar, or similar article embodying my new design. Fig. 2 is an end view of a cigar, or similar article embodying my new design.

The design of my new, original and ornamental cigar, or like article is characterized by the formation of a series of spirally disposed ribs and grooves on the surface of the body of the cigar, or like article and which ribs or grooves give the body of the cigar,

or like article the appearance of being spirally corrugated. To further increase the ornamental effect obtained by corrugating the surface of the cigar, or like article a spirally disposed area on the surface of the body is distinctively colored as compared to the remaining portion or area of the surface of the body.

A cigar, or like article embodying my new and ornamental design has the general appearance of a short section of a rope or cable.

I claim:

The ornamental design for a cigar, or similar article as shown and described.

JOHN K. BRODERICK.

Witnesses:

M. P. SMITH,
B. L. CROWLEY.
